UNITED STATES PATENT OFFICE.

LEO McSWEENEY AND ARTHUR WILSON, OF NEW YORK, N. Y.

COMBINATION BRUSH AND COMB FOR HATS.

Application filed August 25, 1923. Serial No. 659,305.

To all whom it may concern:

Be it known that we, LEO McSWEENEY, a citizen of the United States, and ARTHUR WILSON, a citizen of Australia, both residents of the city of New York, borough of Manhattan, in the county and State of New York, have invented new and useful Improvements in a Combination Brush and Comb for Hats, of which the following is a full, clear, and exact description.

This invention relates to a combination brush and comb for mounting in hats.

The general object of the invention is the provision of a combination brush and comb so constructed that they may be mounted in hats without interfering with the wearing of the hats so as to always be available.

This object is accomplished by providing a hat-engaging member, forming on the upper end of said hat-engaging member a comb-receiving member in which a comb is mounted, and attaching to the comb-receiving member a brush.

This and other objects of the invention will be more clearly understood from the following detailed description and accompanying drawings.

Figure 1 is a perspective view of a hat, showing the combination brush and comb mounted therein;

Figure 2 is a side elevation of the combination brush and comb with a portion broken away to show its construction;

Figure 3 is a vertical section of the combination brush and comb along the line 3—3, Figure 2;

Figure 4 is a horizontal section through the brush and comb holder along the line 4—4, Figure 2.

Referring to the above-mentioned drawings, the invention includes a body 10 made in the form of a plate. This plate has curved sides, as shown in Figure 2. Formed in the lower end of the plate or body 10 is a hat-engaging member 11 made in the form of a curved plate, the curve of the plate conforming to the curve of the hat. Formed on the upper end of the body or plate 10 is a comb-holding member 12. This comb-holding member is formed by providing on the upper end of the body a plate, folding the upper portion of the plate back upon itself, and spacing the folded back portion at a distance from the portion of the plate adjacent the body. The lower edge of the folded-back portion is turned in-

ward providing a bottom wall for the comb-holding member, and the inner portion of the said turned-in member is folded upward parallel to the portion of the plate next the body 10. Thus a pocket is formed for carrying the comb 13. Attached to the comb-holding member 12 and extending parallel to it is a brush 14.

In constructing this combination comb and brush for mounting in hats care would be taken to properly design it for the particular hat in which it is to be mounted. If the combination brush and comb are to be mounted in a felt hat of the fedora type the body 10 could be made long enough to support the brush and comb-holding member between the wall of the hat and the crease usually formed in hats of that type. When the combination brush and comb are designed for straw hats of the sailor type it would be necessary to support the brush and comb-holding member at the top of the hat and close to the wall of the hat. This would be accomplished by making the body 10 of the desired length. It would also probably be necessary to make the bristles of the brush 14 short so as not to interfere with the head of the wearer.

The body 10 and plate 11 present a handle for the brush. In mounting the combination brush and comb in a hat, the plate 12 is inserted between the sweatband 15 and the wall 16 of the hat 17, as shown in Figure 1. Since the plate, body 10 and comb-holding member are made from some light material, such as celluloid or a light metal, the added weight to the hat is not undesirable.

We would state in conclusion that while the illustrated example constitutes a practical embodiment of our invention we do not limit ourselves to the exact details herein illustrated since manifestly the same can be considerably varied without departing from the spirit of the invention as defined in the appended claims.

Claims.

1. As a new article of manufacture, a hat brush and comb carrier comprising a brush head having a comb pocket therein and bristles extending laterally from one side thereof, and a depending handle from said brush head adapted for insertion between the sweatband and the inner side of the crown for positioning the device within the hat to dispose the brush head adjacent the upper

- portion of the crown to prevent contact of the head therewith when the hat is positioned thereon, the said brush head being longitudinally curved to conform to the curvature of the inner side of the crown for snugly fitting thereagainst and for flexing the comb for preventing accidental displacement of the same from the pocket.
2. As a new article of manufacture, a hat brush and comb carrier comprising a brush head having a comb pocket therein and bristles extending laterally from one side thereof, and a depending handle from said brush head adapted for insertion between the sweatband and the inner side of the crown for positioning the device within the

hat to dispose the brush head adjacent the upper portion of the crown to prevent contact of the head therewith when the hat is positioned thereon, the said brush head being longitudinally curved to conform to the curvature of the inner side of the crown for snugly fitting thereagainst and for flexing the comb for preventing accidental displacement of the same from the pocket, the said free end of the handle having an elongated head for engagement with the sweatband to prevent canting of the device when positioned within the hat.
